HYDRAULICALLY ACTUATED RECIPROCATABLE TOOLS

Nils Johan Björnberg, Ektorp, Sweden, assignor to Atlas Copco Aktiebolag, Nacka, Sweden, a corporation of Sweden

Filed July 11, 1961, Ser. No. 123,145
20 Claims. (Cl. 60—51)

This invention relates to improvements in hydraulically actuated reciprocable motors and especially but not exclusively to improvements in motors for operating reciprocating and impact tools, such as portable hammers, drills, pavement breakers and the like.

The primary object of the invention is to provide an improved hydraulically actuated motor which is simple and durable in construction and has a highly efficient pressure fluid distributing system having small hydraulic losses owing to flow resistance.

Another object of the invention is to provide an improved hydraulically actuated reciprocable motor, wherein the reciprocating parts are efficiently sealed so as to eliminate leakage and waste of liquid.

Another object of the invention is to provide an improved hydraulically actuated reciprocable impact tool having a single pressure accumulator inserted for damping pressure fluctuations in the supply as well as in the return line of the tool.

A more specific object of the invention is to provide a hydraulically actuated reciprocable impact tool having a pressure accumulator incorporating spring means in a cylinder acting on a piston for damping pressure fluctuations in said supply and return lines.

Another object of the invention is to provide a hydraulically actuated reciprocable impact motor having damper chambers at the opposed ends of the bore in which the piston is reciprocable, said damper chambers preventing the piston from striking against the motor casing and eliminating the need for special fluid compression means for damping purposes outside of the piston bore on the elongated ends of the piston.

An additional object of the invention is to provide a hydraulically actuated reciprocable impact motor having a pair of totally balanced valves for admitting high pressure fluid to the piston faces and connecting said piston faces to a low pressure fluid outlet, respectively, having a single hydraulic motor drive-coupled to and synchronizing the movement of said valves.

Another object of the invention is to provide a gear motor or pump for operating said valves or for other purposes having hydraulically balanced intermeshing gears in order to reduce the friction at the high pressure fluid inlet portion of the gear motor or pump.

The above and other objects of the invention will become obvious from the following description and from the accompanying drawings in which an embodiment of the invention is illustrated by way of example. It should be understood that this embodiment is only illustrative of the invention and that various modifications may be made within the scope of the claims without departing from the scope of the invention.

In the drawings, wherein like parts are designated by like reference characters throughout the several views, FIG. 1 is a longitudinal sectional view of a hydraulically actuated reciprocable impact tool embodying the invention; FIG. 2 is a fragmental enlarged view of the cylinder section in FIG. 1; FIG. 3 is a fragmental enlarged view of the accumulator section in FIG. 1; FIG. 4 is an enlarged sectional view of the valve casing on line 4—4 in FIG. 5; FIG. 5 is a sectional view on line 5—5 in FIG. 4; FIG. 6 is a sectional view on line 6—6 in FIG. 4; FIG. 7 is a transverse sectional view through the gear motor for ro-

2

tating the valve system and shows diagrammatically the connections of the motor to the pressure fluid supply and return passages; FIG. 8 is a fragmental perspective view of one of the gear wheels of FIG. 7; and FIGS. 9—12 are fragmental sectional views through the valve system in four different valve positions during a full operating cycle of the impact tool.

Referring specifically to the drawings, the tool shown in FIG. 1 is provided with a composite casing which may be portable or may for power feeding purposes be mounted on a suitable feeding device. The composite casing incorporates a central cylinder section 11 having centrally therethrough a cylinder bore 12 and carrying in coaxial arrangement a rear section 13 and a front member 14, the latter having a forwardly directed chuck section 15. The parts 11, 13, 14 and 15 of the composite casing are as conventionally firmly clamped together by means of bolts, not shown.

Inside of the cylinder section 11 there is provided a piston head 16 having a sliding fit in the cylinder bore 12 and being provided with forwardly and rearwardly extending elongated ends or stems 17 and 18. The rearwardly extending elongated end 18 has preferably a smaller diameter than the opposed elongated end 17, thereby providing a somewhat greater surface on the rear face of the piston head 16 to be actuated upon by incompressible fluid under pressure than provided on the forward face of the piston head. Preferably the piston head 16 has a maximum diameter of 1.3 times the diameter of the elongated end 18. Leakage along the elongated ends is prevented by annular end members or sealing blocks 19 and 20 of steel provided with outer ring seals 21 on the forward and rearward portion of the outer mantle of the respective sealing block, FIG. 2. The blocks 19, 20 are held with some small play in enlarged bores 22 in the cylinder section 11 with the ring seals 21 tightening thereagainst.

The blocks are held in place by suitable extensions on the front member 14 and rear section 13 and the play between the blocks and the cylinder section provides access for a small portion of the incompressible fluid from the cylinder bore 12 to the outer mantle of the blocks 19—20 as far as to the ring seals 21. The annular inner surface of each block 19, 20 has a tight sliding fit around the pertaining elongated end 17, 18 of the piston head 16. Adjacent the sealing blocks 19, 20 there are arranged annular damper chambers 23 in alignment with the bore 12 and provided for absorbing the energy of the piston head 16 at each end of its strokes in the direction of the sealing blocks 19, 20. To this end the damper chambers may have a diameter slightly greater than the diameter of the piston head 16 or bore 12, for example 0.2 mm. greater, so that pressure fluid trapped in the chambers 23 may be expelled by the moving piston head through the annular opening surrounding the head, such action being performed under increasing resistance as the piston head penetrates deeper into the damper chamber. Between the opposed ends of the bore 12 and the blocks 19 and 20 there are formed short radial inlet passages 24 and 25 and suitable annular grooves for the admission of high pressure fluid into the working chambers of the bore 12 or for the emptying of low pressure fluid.

Inside of the chuck section 15 there is provided a rotary chuck 26 which may be rotated by a motor preferably a conventional gear type hydraulic motor indicated at 27, which may be of well known construction and consequently is not shown in detail. The rotary chuck 26 cooperates with and rotates the shank of the drill steel 28 which is provided with an axial passage 29 therethrough for the flushing fluid. A liquid conducting tube 30 extends from the rear section 13 through an axial bore 30¹

through the piston head and its elongated ends and penetrates at its tip into the passage 29 of the hollow drill steel 28. A hose terminal 31 for the connection of a water hose is provided at the rear portion of the section 13 and is connected thereto by means of a cylindrical threaded plug 321. From the hose terminal 31 the flushing fluid is directed into the flushing tube 30 and passes therefrom into the hollow drill steel 28.

On the cylinder section 11 there is a radially protruding portion with an open ended cylindrical aperture 32 into which there is inserted a valve housing 33. The housing 33 is kept in place by means of a sealing abutment for the aperture 32 on an accumulator section 34. The section 34 is connected to the radially protruding portion of the cylinder section 11 by means of bolts, not shown. A high-pressure fluid connection 35 and a low-pressure fluid connection 36 are connected to the accumulator section 34 and lead to a bore 38 provided therein. A piston 37 is reciprocably arranged in the bore 38 and its opposed faces are acted upon by high-pressure fluid and low-pressure fluid, respectively. In order to balance the piston 37 against the overpressure at the connection 35, there are provided annular elastically flexing spring discs 40 in bellows arrangement between an end closure 39 for the bore 38 and the low-pressure face of the piston 37. A flexible springy stop ring 41, FIG. 3, is inserted through a tangential perforation into aligned annular grooves formed on the peripheries of the end member 39 and bore 38 in order to keep the end closure 39 in place in the bore 38.

The precompression and the elastic properties of the spring disc arrangement may be chosen to give a constant spring force resulting compression of the spring discs 40. The discs are grouped around a hollow axially extended portion 42 of the piston 37, the end of the portion remote from the piston 37 being slidably supported by a bearing 43 on the closure member 39 also acting as an abutment for the discs. Suitable perforations are provided in the mantle of the extended portion 42 as well as in the base of the bearing 43 in order to secure free circulation of pressure fluid. At the high-pressure face of the piston 37 there is provided an extension 44 cooperating with and resting against the housing of the accumulator section 34 when the pressures on opposed sides of the piston 37 are equalized. The aggregate of spring discs 40 is divided into two groups which are separated by a cylindrical spacing member 45 adjacent the connection 36 in order to provide for free pressure fluid flow transversely through the accumulator section 34. A high-pressure passage 46 and a low-pressure return passage 47 are provided between the bore 38 and the valve housing 33 and are connected to the bore at opposed sides of the accumulator piston 37.

The high-pressure passage 46 is in constant communication with the interior 48¹ of a rotary automatic control valve 48 extending axially of the valve housing 33 while the interior 49¹ of a similar control valve 49 arranged in spaced-apart parallel relationship with the valve 48 is in constant communication with the low-pressure passage 47. The control valves 48 and 49 are formed hollow and cylindrical and are provided with diametrically opposed valve slits 50.

Two intermeshing gear wheels 51, 52 of a gear motor are made integral with the control valves 48, 49. Each gear wheel 51, 52 is supported by and fits snugly into a cylindrical aperture 53 in the control valve housing 33 and is pivotally supported by a cylindrical hollow journal 54 extending in concentric relation with respect to the cylindrical apertures 53. The hollow journals 54 form intermediate passages between the interior of the control valves 48, 49 and the inlet and outlet passages 46, 47, respectively. Radially extending flanges 55 on the journals 54 form closures for the apertures 53 and are clamped in place between the accumulator section 34 and the valve casing 33. Between each flange 55 and the bottom of the aper-

tures 53 there is formed a working space for the two intermeshing gear wheels 51, 52 of the gear motor. A passage 56 leads from the high-pressure fluid passage 46 to the high-pressure fluid side of the gear motor, while its low-pressure fluid side is vented to the outlet passage 47 by means of a passage 57. The pressure fluid flow passing the passage 56 for driving the gear motor is coupled in parallel with respect to the main flow for driving the piston 16. Slidably inserted into the passage 56 is a piston shaped valve 58 having a number of axial perforations 59 for throttling the flow therethrough and a forwardly protruding tip 60. The tip 60 coacts with a restricted portion 62 of the passage 56 and is prevented from closing said restricted portion 62 by means of a helical spring 61 which is supported between the valve 58 and a shoulder adjacent the portion 62. When, in order to start the gear motor 51, 52, high-pressure fluid is admitted to the passages 46 and 56, the valve 58 is acted upon by the pressure differential set up by the throttling effect of the perforations 59 upon the flow and, as a result, the valve is displaced in the direction of the flow compressing the helical spring 61. While the building up of the pressure differential and the displacement takes place, a comparatively large quantity of pressure fluid is able to pass through the perforations 59 of the valve 58 and the passage 62 in order to act for starting purposes on the gear motor 51, 52. With increasing compression of the helical spring 61, however, the tip 60 of the valve 58, while penetrating into the passage 62 until the fluid and spring forces acting on the valve are balanced, begins to exert a throttling effect against the passage 62. Said throttling effect is increased with increased compression of the spring by the fluid flow and decreased as the spring expands and, as a result, there is attained a keeping of the fluid flow through the motor 51, 52 almost constant and at a level defined by the tension of the spring 61 and diameter of the perforation 59 notwithstanding the fact that there may occur considerable pressure fluctuations in the supply passage 46. Consequently, there also is attained an almost constant rotational speed of the two control valves 48 and 49 intercoupled by the gear wheels 51, 52.

In order to make possible an efficient balancing of the intermeshing gear wheels with respect to the different pressures acting on the wheels there are provided radial perforations 63 at the bottom between the gear teeth which perforations lead through said gear wheels to cushion forming recesses 64 turned into the direction of the journals 54, FIGS. 4 and 8. The pressure acting at the high-pressure end of the motor tends to press the gear wheels 51, 52 radially against their journals 54 thereby creating frictional resistance to rotation. Simultaneously, however, there is a counter pressure acting in the recesses 64 with the result that an efficient balancing of the pressures is attained and a minimum power is required to rotate the gear motor 51, 52. The intermeshing teeth of the gears 51, 52 form an efficient means to synchronize the rotation of the two control valves 48 and 49.

Opening up into the direction of the cylinder section 11 there are arranged in the valve housing 33 two parallel axially extending chambers 24¹ and 25¹, the chamber 24¹ communicating with the inlet 24 of the cylinder bore 12 while the chamber 25¹ is in communication with the corresponding inlet 25. The rotating control valves 48 and 49 are in their turn rotatably nested in valve bores 65 and 66 arranged at the opposite side of the valve casing 33 with respect to the chambers 24¹ and 25¹. In order to make smooth operation of the valves 48 and 49 possible while distribution of the pressure fluid to and from the respective chambers 24¹, 25¹ and inlets 24, 25 takes place, there are arranged passages for balancing of the pressures acting upon these valves in every direction and under all conditions of operation. To this end there are provided pairs of diametrically opposed and interconnected distributing grooves in the valve bores 65 and 66 by which equalization of pressures during the operation of the valves is effected. Adjacent the control valve 48, the interior 48¹

of which is in permanent communication with the high-pressure inlet 46, there are arranged the opposed axial distributing grooves 67 for feeding the chamber 25¹ and, consequently, the inlet 25 with high-pressure fluid, there being performed a pressure equalization between the opposed grooves 67 through a peripheral groove 68 in the valve housing 33, FIG. 5. A second pair of opposed distributing grooves 69 is provided in the valve bore 65 for feeding the chamber 24¹ and the inlet 24 with high-pressure fluid, there being likewise provided a peripheral groove 70, FIG. 6 in the valve housing 33 for equalization of the pressures acting in the grooves 69 of the valve 48. In the valve bore 66 of the valve 49, the interior 49¹ of which is in permanent communication with the low-pressure exhaust passage 47, there are in full analogy arranged the opposed distributing grooves 71 for connecting the chamber 24¹ and consequently the inlet 24 to the exhaust passage 47, pressure equalization between the grooves 71 being performed by means of a peripheral groove 72, FIG. 5, while opposed peripheral additional grooves 73 are arranged for connecting the chamber 25¹, i.e., the inlet 25 to the passage 47. The pressures in the grooves 73 are equalized by means of a peripheral groove 74, FIG. 6. For balancing the ends of the valves 48, 49 adjacent the gears 51, 52 there are arranged perforations 75 through the journals 54, FIG. 4.

Prior to operation the tool has to be connected by means of the inlet and exhaust connections 35, 36 as well as by the connections leading to the drill chuck motor 27, to a suitable hydraulic supply incorporating a continuously functioning hydraulic pressure producer or pump delivering high-pressure fluid at a substantially constant pressure. Such hydraulic pressure producer together with its auxiliary equipment such as a suitable reservoir, liquid filters, pressure regulating valves and their arrangement are well known in the art and will not be described here. Likewise there is given no description of the conventional throttle valve connected in parallel between the inlet connection and the exhaust connection at a suitable place and providing a by-pass for returning the continuous fluid flow to the supply reservoir in the non-operative position of the throttle valve.

In operation, as soon as the throttle valve is brought into its operating position, high-pressure fluid is supplied through the connection 35 to the high-pressure face of the accumulator piston 37 in the bore 38 and therefrom through the high pressure passage 46 into the interior of the valve 48. Simultaneously, high-pressure fluid passes from the passage 46 into the passage 56 and to the gear motor 51, 52 starting the rotational movement of the synchronized valves 48, 49. During rotation of the valves 48, 49 high-pressure fluid is alternately delivered by means of the valve 48 to the inlets 24 and 25 of the cylinder bore 12 while simultaneously the other of the two inlets 24, 25 is alternately connected to the exhaust passage 47 by means of the other control valve 49. The operation of the valves is shown more in detail in FIGS. 9-12 inclusive, in which a revolution through almost 180° of the valves 48, 49 is depicted. During such half revolution a full operating cycle of the piston 16, 17, 18 is performed. Assuming the piston to be in the position of FIG. 1 which corresponds to the valve position shown in FIG. 9, high-pressure fluid flowing to the valve 48 passes from its interior 48¹ through its slits 50 into the axial grooves 60 and therefrom partly through the balancing groove 70 and partly directly into the chamber 24¹ and on through the inlet 24 to the forward face of the piston head 16. Simultaneously, the rear face of the piston head is brought into communication with the exhaust passage 47 through the inlet 25, the chamber 25¹, the balancing groove 74, the axial grooves 73, the valve slits 50 and the interior 49¹ of the valve 49. From the passage 47 the low-pressure fluid passes transversely through the bore 38 of the accumulator section 34 past the distance ring 45 to the low-pressure fluid connection 36. The pressure fluid acting

on the forward face of the piston head 16 displaces the piston rearwardly and performs the return stroke. During the continuous rotation of the valves 48, 49 next the position shown in FIG. 10 is passed. This is the switching over position, in which the peripheral portions of the valve bores 65, 66 are passed by the valve slits 51 during their travel to the following pair of axial grooves 67 and 71, and the flow is switched over from the forward piston face of the piston head 16 to the rearward. During this action the piston 16-18 is travelling with great velocity to the rear and compresses the pressure fluid at the rear face of the piston head 16 thereby forcing said fluid as the switching over of the valve 48 is completed against the pressure of the fluid in the valve 48 back through the interior 48¹ of the valve 48. In effect the piston, while being retarded, now pumps pressure fluid from the rear face of the piston head 16 through the valve 48 to the accumulator bore 38. By compression of the spring discs 40 the accumulator takes up the pressure fluid returning from the cylinder bore 12 through the passage 46 as well as streaming from the pressure producer through the inlet connection 35. Subsequently the piston 16-18 is finally stopped by the pressure fluid acting on the rear face of the piston head 16, and in the valve position shown in FIG. 12 and there begins an acceleration of the piston in forward direction in order to perform an impact against the drill shank 28. As seen, pressure fluid from the inlet connection 35 as well as from the high-pressure side of the filled accumulator may now pass through the valve 48 in order to be directed via the grooves 67 to the inlet 25 and the rear face of the piston head 16, simultaneously with the forward face of the piston being connected to the exhaust connection 36 over the inlet 24, the valve 49, and the low pressure side of the accumulator. At the moment of impact the valves 48, 49 are in the position shown in FIG. 12. The piston is now practically stationary as it has given up its energy of motion to the drill shank and consequently there is performed no subsequent pumping action back through the valve 48 to the accumulator. At the next instant the valves 48 and 49 turn into a position corresponding to the position shown in FIG. 9, which means the beginning of a new impact cycle.

As readily seen, the pressure accumulaton during operation of the tool absorbs high pressure peaks and inertial fluid shocks resulting from the operation of the valves 48, 49 and the piston 16-18. Likewise it takes up and stores pressure fluid at instants when such pressure fluid may not pass to the faces of the moving piston while it delivers pressure fluid to the cylinder bore at instants when the pressure producer fails to fully cover the fluid quantity needed.

Apparently the energy originally fed through the control valve system for performing the return stroke has to be exchanged or pumped through the valve casing in the form of pressure fluid not less than three times, that is to say firstly from the high pressure side to the front face of the piston head during the return acceleration, subsequently from the rear face to the pressure accumulator during retardation of the return stroke and finally back again from the pressure accumulator to the rear face of the piston head during acceleration of the piston in order to perform an impact. Consequently, an important feature for the efficient operation of the impact tool described is the provision for small flow resistances in the control valve system. As readily seen the fluid passages in the valve system are formed with wide cross-sectional areas and as short as possible permitting the pressure fluid to flow with a minimum of disturbances. The pressure peaks generated are utilized for loading up the pressure accumulator which subsequently returns its stored energy to the piston. The pressure accumulator greatly moderates the peak pressures acting at the high pressure fluid inlet 46, so that no excessive pulsations may be reflected out through the inlet and outlet connections 35, 36. Owing to the coupling of the pressure accumulator in

parallel with the valve system excessive pressure pulsations in the exhaust passage 47 may also be equalized by the accumulator.

Occasionally during operation as well as during idling of the tool the piston head 16 may be thrown past its usual reversal and stopping points in which case the damper chambers 23 will prevent the piston from hitting against the ends of the tool casing or the blocks 19 and 20. As the piston head penetrates into the damper chambers the pressure generated therein will act on the outer mantle of the blocks owing to the play between the blocks 19, 20 and the cylinder section 11 and will compress the blocks inwards thereby increasing the sealing action of the steel blocks 19 and 20 and counter-acting the high-pressure tending to give rise to leakage. The high-pressure generated in the damper chambers is confined to the chambers and unable to act on the control valve system.

The hydraulically actuated reciprocable impact motor described and illustrated in the drawings should only be considered as an example and the invention may be modified in several different ways within the scope of the following claims.

What I claim is:

1. In a hydraulically actuated reciprocable impact motor, a casing having a bore, a piston head reciprocable within said bore and having a sliding fit therein, said piston head having opposite faces alternately exposable to incompressible fluid under pressure, opposed elongated free ends on said piston head, said ends being axially unaffected by fluid under compression, the piston head having maximally a diameter 1.3 times the minimum diameter of said elongated ends, an end member in said casing at one end of said bore providing a seal between said casing and one of said elongated ends, hydraulic damper means between said bore and said end member for absorbing the energy of said piston at the end of its stroke in the direction of said end member, a high-pressure fluid inlet and low-pressure fluid outlet associated with said casing, a first totally balanced valve associated with said casing in proximity to said bore, said first valve in constant communication with said inlet and being movable to alternately admit said high-pressure fluid to said opposed piston faces, a second totally balanced valve associated with said casing in proximity to said bore, said second valve in constant communication with said outlet and being movable to alternately connect said opposed piston faces to said low-pressure fluid outlet, a single hydraulic gear motor associated with said casing, said gear motor drive-coupled to and synchronizing the movement of said valves, means for hydraulically balancing the gears of said gear motor, and a single pressure accumulator coupled between said inlet and outlet to respond to pressure fluctuations in said inlet as well as in said outlet.

2. In a hydraulically actuated reciprocable impact motor, a casing having a bore, a piston reciprocable within said bore and having opposed faces alternately exposable to incompressible fluid under pressure, an elongated end on said piston, an end member in said casing at one end of said bore providing a seal between said casing and said elongated end, a passage adjacent the end of said bore and axially spaced therein from said end member for introducing and withdrawing said fluid into and from said bore, distributing means associated with said casing to alternately admit and withdraw said fluid through said passage for reciprocating said piston, and an annular damper chamber in said bore and axially between said passage and said end member, said damper chamber having a diameter slightly greater than said bore for absorbing the energy of said piston at the end of its stroke in the direction of said end member.

3. In a hydraulically actuated reciprocable impact motor, a casing having a bore, a piston reciprocable within said bore and having opposed faces alternately

exposable to incompressible fluid under pressure, an elongated end on said piston, an annular sealing block in said casing at one end of said bore providing a seal between said casing and said elongated end, distributing means associated with said casing to alternately admit said fluid to said opposite piston faces for reciprocating said piston, hydraulic damper means between said bore and said block for absorbing the energy of said piston at the end of its stroke in the direction of said block, and a connection between said damper means and the outside of said block providing access for said fluid to compress said block inwardly in radial direction.

4. In a hydraulically actuated reciprocable impact motor, a casing having a bore, a piston reciprocable within said bore and having opposed faces alternately exposable to incompressible fluid under pressure, an elongated end on said piston, an annular sealing block in said casing at one end of said bore providing a seal between said casing and said elongated end, distributing means associated with said casing to alternately admit said fluid to said opposite piston faces for reciprocating said piston, an annular damper chamber having a diameter slightly greater than said bore between said bore and said block for absorbing the energy of said piston at the end of its stroke in the direction of said block, and a connection between said damper chamber and the outside of said block providing access for said fluid to compress said block inwardly in radial direction.

5. In a hydraulically actuated reciprocable impact motor, a casing having a bore, a piston reciprocable within said bore and having opposed faces alternately exposable to incompressible fluid under pressure, opposed elongated ends on said piston, annular sealing blocks in said casing at the opposite ends of said bore providing a seal between said casing and said elongated ends, distributing means associated with said casing to alternately admit said fluid to said opposite piston faces for reciprocating said piston, an annular damper chamber having a diameter slightly greater than said bore between said bore and each block for absorbing the energy of said piston at the end of its strokes, and a connection between said damper chambers and the outside of said blocks providing access for said fluid to compress said block inwardly in radial direction.

6. In a hydraulically actuated reciprocable impact motor, a casing having a bore, a piston head reciprocable within said bore and having a sliding fit therein, the piston head having opposite faces alternately exposable to incompressible fluid under pressure, opposed elongated constant diameter stems on said piston head, said stems extending axially throughout said bore and being axially unaffected by fluid under compression, the piston head having maximally a diameter 1.3 times the minimum diameter of said elongated stems of said piston, annular sealing means in said casing at the opposite ends of said bore providing a seal between said casing and said elongated stems, and distributing means associated with said casing to alternately admit said fluid to said opposed piston head faces for reciprocating said piston, said piston being substantially freely sliding in said bore and said stems being free of mechanical connections with other parts.

7. A hydraulically actuated reciprocable impact tool comprising in combination, a casing having a bore, a piston reciprocable within said bore and having opposed faces alternately exposable to incompressible fluid under high pressure, a high-pressure fluid inlet and low-pressure fluid outlet associated with said casing, a first totally balanced valve associated with said casing in proximity to said bore, said first valve in constant communication with said inlet and being movable to alternately admit said high-pressure fluid to said opposed piston faces, a second totally balanced valve associated with said casing in proximity to said bore, said second valve in constant communication with said outlet and being

movable to alternately connect said opposed piston faces to said low-pressure fluid outlet, and a single hydraulic motor associated with said casing, said motor drive-coupled to and synchronizing the movement of said valves.

8. A hydraulically actuated impact tool as claimed in claim 7, wherein said hydraulic motor consists of a rotary gear-type motor having two oppositely rotating gears each of them drive-coupled to one of said valves.

9. A hydraulically actuated impact tool as claimed in claim 7, wherein each valve incorporates a central cavity, said cavity being in constant communication with said inlet and outlet, respectively.

10. A hydraulically actuated impact tool as claimed in claim 8, wherein said drive-coupled gears and valves are integral and incorporate a central cavity, said cavity being in constant communication with said inlet and outlet, respectively.

11. A gear motor comprising a casing, cylindrical journals in said casing, two intermeshing oppositely rotating gears journaled in said journals in said casing and fitting snugly therein, a high-pressure fluid inlet and a low-pressure fluid outlet at opposite sides of the intermeshing portion of said gears, said journals being concentric with said gears, and means including radial perforations through said gears and connecting said fluid inlet with said journals for hydraulically balancing said gears by leading high-pressure fluid from said fluid inlet to said journals.

12. A gear motor as recited in claim 11 in which said gears are provided with pressure fluid cushion-forming recesses adjacent said perforations and facing said journals.

13. In a hydraulically actuated reciprocable impact motor, a casing having a bore, a piston reciprocable within said bore, a piston head on said piston having a sliding fit in said bore, said piston head having opposed faces alternately exposable to incompressible fluid under pressure, an elongated end on said piston, an end member in said casing at one end of said bore providing a seal between said casing and said elongated end, distributing means associated with said casing to alternately admit said fluid to said opposite piston faces for reciprocating said piston, passages at the opposed ends of said bore for the admission thereto and emptying therefrom of said fluid, annular damper chambers having a diameter slightly greater than said bore at the opposed ends of said bore and axially beyond said passages for absorbing the energy of said piston at the ends of each stroke in the direction of said damper chambers, and annular circumferential grooves adjacent said damper chambers and in flow communication with said passages for receiving said fluid from said chambers as said piston head moves therein.

14. In a hydraulically actuated reciprocable impact motor, a casing having a bore, a piston reciprocable within said bore, passages in said casing for conducting incompressible fluid under pressure to said bore for reciprocating said piston, an elongated end on said piston, an end member in said casing at one end of said bore providing a seal between said casing and said elongated end, distributing means associated with said casing to admit said fluid to said passages for reciprocating said piston, a cylindrical enlargement on said piston forming a surface disposed transversely to the longitudinal axis of said piston, an annular damper chamber adjacent said end member, said damper chamber having a diameter slightly greater than said enlargement for receiving said enlargement with the formation of a narrow annular opening therearound thereby to absorb the energy of said piston at the end of its stroke in the direction of said end member, and an annular circumferential groove in said bore axially spaced from said end member and in flow communication with said passage adjacent thereto

for receiving fluid from said annular opening as said enlargement moves into said chamber.

15. In a hydraulically actuated reciprocable impact motor, a casing having a bore, a piston reciprocable within said bore, passages in said casing for conducting incompressible fluid under pressure to the opposed ends of said bore for reciprocating said piston, an elongated end on said piston, an end member in said casing at one end of said bore providing a seal between said casing and said elongated end, distributing means associated with said casing to admit said fluid to said passages for reciprocating said piston, a piston head on said piston forming opposed faces disposed transversely to the longitudinal axis of said piston, annular damper chambers at the opposed ends of said bore axially beyond said passages, said damper chambers having a diameter slightly greater than said piston head for receiving said head with the formation of a narrow annular opening therearound thereby to absorb the energy of said piston at the end of its stroke in the direction of said damper chambers, and annular circumferential grooves in said bore adjacent said chambers and in flow communication with said passages for receiving the said fluid from said annular openings as said piston head moves into said chambers.

16. In a hydraulically actuated reciprocable impact tool, a casing having a bore, a hammer piston reciprocable within said bore and having opposed faces alternately exposable to incompressible fluid under high pressure, a high pressure fluid inlet and a low pressure fluid outlet in said casing, distributing valve means rotatably disposed adjacent said casing in communication with said inlet and outlet for continuously rotating and alternately admitting said high pressure fluid to said opposed piston faces and alternately connecting said opposed piston faces to said low pressure fluid outlet, a cylinder immediately adjacent and between said inlet and said outlet, an accumulator piston reciprocable within said cylinder and having one side fully exposed to high pressure fluid and the other side fully exposed to low pressure fluid, and annular elastically flexing spring discs in bellows arrangement at the opposite side of said accumulator piston in said cylinder for balancing said accumulator piston against the pressure of the high pressure fluid.

17. In apparatus of the character described for supplying incompressible fluid to opposite sides of the reciprocating piston of an impact tool and for accommodating sudden pressure peaks in the inlet and outlet therefor, and having a casing with a bore, a hammer piston reciprocable in said bore having opposed faces alternately exposable to incompressible fluid under high pressure, a high pressure fluid inlet in said casing, and a low pressure fluid outlet in said casing, the combination which comprises distributing valve means disposed in said casing adjacent said inlet and said outlet and connected therebetween for continuously and alternately connecting said high pressure inlet and said low pressure outlet to said opposed sides of said reciprocating piston respectively, a fluid pressure motor connected to said distributing valve means for actuating said valve means, and a single pressure accumulator disposed adjacent said valve and in parallel flow communication therewith and with said inlet and said outlet for accumulating pressure fluid to accommodate pressure fluctuations in said inlet as well as said outlet caused by the operation of said valve.

18. In apparatus of the character described for supplying incompressible fluid to opposite sides of the reciprocating piston of an impact tool and for accommodating sudden pressure peaks in the inlet and outlet therefor, and having a casing with a bore, a hammer piston reciprocable in said bore having opposed faces alternately exposable to incompressible fluid under high

pressure, a high pressure fluid inlet in said casing, and a low pressure fluid outlet in said casing, the combination which comprises distributing valve means disposed in said casing adjacent said inlet and said outlet and connected thereto for continuously and alternately connecting said high pressure inlet and said low pressure outlet to said opposed sides of said reciprocating piston respectively, a fluid pressure motor connected to said distributing valve means for actuating said valve means, a cylinder disposed adjacent said valve means and in parallel flow communication therewith and with said inlet and said outlet for accumulating pressure fluid to accommodate pressure fluctuations in said inlet as well as said outlet caused by operation of said valve, an accumulator piston reciprocable with a tight sliding fit within said cylinder and having one side thereof fully exposed to high pressure fluid and the other fully to low pressure fluid, respectively, and spring means within said cylinder for balancing said accumulator piston against the pressure of the said high pressure fluid therein.

19. Apparatus as recited in claim 18 in which said spring means consists of a plurality of annular elastically flexing spring discs in bellows arrangement.

20. Apparatus as recited in claim 18 in which the fluid flow to and from said inlet and said outlet is di-

rected to traverse said cylinder at opposite sides of said accumulator piston.
